CLAIM

The ornamental design for a combined puncher, stapler and holder for desk utensils, as shown and described.

DESCRIPTION

FIG. 1 is a left front perspective view of a combined puncher, stapler and holder for desk utensils showing my new design;

FIG. 2 is a right side elevational view thereof;

FIG. 3 is a rear elevational view; and

FIG. 4 is a right front perspective view thereof.

The bottom surface not shown is plain and unornamented.
